FIG. 1.

FIG. 2.

To all whom it may concern:

Be it known that I, Herbert S. Barnhart, a citizen of the United States, residing in Scarsdale, county of Westchester, and State of New York, have invented a new, original, and ornamental Design for a Lazy Susan or Similar Article, of which the following is a specification, reference being had to the accompanying drawing, forming a part thereof. In the drawing:

The parts shown in full lines in Figure 1 are continued about the periphery.

I claim:

The ornamental design for a Lazy Susan or similar article, as shown and described.
